LAMP SHADE AND METHOD FOR MAKING
THE SAME

Joseph M. Angeletti, New York, N. Y.

Application March 31, 1932. Serial No. 602,263

10 Claims. (Cl. 240—108)

This invention relates more particularly to accordion-plaited lamp-shade-coverings, and the main object of the improvement is to provide a covering of the above character capable of being expanded for use without the necessity of a supporting frame which is indispensable with accordion-plaited lamp-shade-coverings of the ordinary construction.

Another object of the invention is to form said covering, with a circumferentially expandable flange portion which, in addition to rendering the covering self-supporting, increases the decorative appearance of the covering when expanded for use.

The invention contemplates also the provision of a preferred means to economically fold a longitudinal marginal portion of the material forming the covering, before plaiting the same. The illustrated and described means are not claimed in this application and that the same may be of any other suitable construction.

Other objects will be apparent as the description proceeds.

In the drawing:—

Fig. 1 is a side detail view of one form of plaited lamp shade covering embodying my invention, expanded for use.

Fig. 2 is a front detail view of the scoring and folding device used in the production of the lamp shade covering embodied by my invention.

Fig. 3 illustrates one of the scoring and folding wheels and associated bearing used in the scoring and folding device, removed.

Fig. 4 is a perspective of a folded and plaited blank forming the covering.

Fig. 5 is a fractional side elevation of the covering mounted on a lamp-bearing-top.

Fig. 6 is a perspective of the complete lamp-shade-covering embodied by my invention, when its plaits are contracted and banded for packing or transportation.

Fig. 7 is a diagrammatic illustration showing three of the various shapes this covering may be made by simply varying the dimension of the two relative portions of the covering.

Describing the preferred means for producing the lamp-shade-covering embodied by my invention, reference may be had to the scoring and folding device shown in Fig. 2, which comprises, lateral supporting arms 10 and 11, preferably secured rearwardly at the sides of a plaiting machine (not shown) and in line with the travel or motion of the web or strip drawn from a material supply roll (not shown) and which is to be plaited by said machine. Secured on

said arms is a transverse bar 12 which is preferably of a rectangular cross sectional form. Adjustably supported on said bar are two complementary pairs of arms 13 and 14 which extend downwardly from the bar. Arms 13 have 60 bearings 15 which have an inclination toward a common center and rotatably support wheels 16 which are formed with a cylindrical V shape groove 17.

Arms 14 have a portion 18 bent angularly toward arms 13, and at the bent portion of said arms is a socket 19 to receive the shank portion 20 of bearings 21 which rotatably support wheels 22, the latter formed with a cylindrical V shape edge to rotate in grooves 17 of wheels 16. Screws 23 threaded on sockets 19 abut against flat portion 24 of shanks 20 to secure the same in adjusted positions. Preferably formed on transverse bar 12 are graduations 25 to facilitate transverse adjustments of said wheel-bearing arms to allow different widths of strip material 26 to be fed through said wheels, thence through the plaiting machine. Said material may consist of stiff paper, parchment-paper, stiff textile, or any other plaitable strip material suitable for lamp-shades, be it plain, printed, or otherwise decorated materials.

The operation of the above described device is as follows:—

Knowing the width of the strip of material 26, 85 and the width of the longitudinal marginal portions 27 and 28 to be scored and folded, I set the wheels of said device accordingly, guided by graduations 25 on bar 12, and of course, the material supply roll is set in line with the adjusted device. The strip is inserted between said wheels, as at Fig. 2, and the scoring-pressure for the material is also regulated by lifting or lowering wheels 22 through the medium of their bearing shank portion which is bossed by screws 23, so as 90 to bring the peripheral or cylindrical V shape edge of the wheels nearer to or farther from the grooves of wheels 16, according to the thickness of the material. The folded forward end of the latter is then advanced alternately above and below material stretching or tensioning transverse rods or bars (not shown) but which accordion-plaiting machines have, and which are equipped with side-guides adjustable on said rods or bars. The strip is further advanced between said guides 100 which are set in line with said device. The scored and folded portions 27 and 28 will then be sufficiently flattened and so inserted between the pusher-bar and cooperating plate of the plaiting machine by the actuation of which, the strip 105 110

material is continuously pulled from the supply-roll and thru said device, and plaited transversely of the folds. The folded and plaited strip is then cut into blanks according to the number of the plaits the covering is wanted to contain, one of said blanks is shown in Fig. 4. The blank is then joined annularly by securing end-plait 29 above end-plait 30, in any suitable manner, or by staples 31, as at Fig. 1, with folded portion 27 capable of being expanded outwardly from the interior of the annular covering. The latter is then contracted with folded portion 27 at its normal folded position, as at Fig. 6, to form perforations 32 throughout all of the plaits and thru folded portion 28, by means of a suitable drilling or perforating machine, said perforations to receive a binding element 33, which may be of any suitable construction, though, in the preferred embodiment, the binding element is of an elastic construction and pre-adjusted by knotting the same, as at 34 Fig. 6, to limit its expansion, at the same time to force the perforated end portion of the plaits against the frusto-conical annular flange portion 35 of a lamp-bearing-element 36, which may be of any suitable construction, in a circumferential contracted position, as at Fig. 5. In the form illustrated, the top-element is formed with an annular rim portion 37, which encircles the narrow annular portion of flange 35, and projects outwardly to bear above the contracted end portion of the plaits, forming retaining connection therewith. The outer edge of said rim is preferably curled or beaded as at 38, to prevent injury to the covering when the rim portion is forced from the interior throughout the contracted end of the covering. Fastened on flange 35, is a lamp-bearing member 39 which may be of any desired form, the one illustrated is usually employed on table-lamps. As the above described covering retains its circumferential expanded position when folded portion 27 is expanded, as at Fig. 1, it is obvious, that inserting the reduced or contact portion of an ordinary electric-lamp thru the contracted end of the covering, and screwing the lamp to the lamp-socket, the covering is actually mounted for use. It is also to be understood that while the above description has been confined in the usability of this covering without the employment of frames, as are indispensable for the ordinary-plaited lamp-shade coverings, the one embodied by my invention, is also capable to receive and bind with frames of any desired shape. As obvious, folded portion 28 serves only to have both longitudinal marginal portions of the web or strip material of same thickness, to equalize its feed thru said parts and thru the plaiting machine. Said additional folded portion however, renders the perforated portion of the plaits stronger, rendering possible the use of a stronger elastic-binding element.

Diagrammatic Fig. 7, shows a few examples of the various shapes this covering may be made, by simply varying the dimension of the folded portion 27, and that of the upper portion of the plaits, while retaining the same number of plaits which determines the diameter of the covering, as in dotted lines 1—1, 2—2 and 3—3.

As it may be easily seen in the drawing, when folded portion 27 is expanded outwardly circumferentially, the upper transverse edges 40, of its plait portions, will be downwardly disposed, but in line with the lower transverse edges 41 of the contracted plait portion of the covering. Said counter-plait-point at the circumferentially expanded fold, causes the latter to retain expand-

ed position when the folded portion is forced outwardly from the interior of the covering.

In the above I have described the preferred embodiment of my invention, but I do not wish to be misunderstood as limiting myself thereto as I am aware that modifications may be made therein without departing from the principle or sacrificing any of the advantages of this invention, therefore, I reserve to myself the right to make such changes as fairly fall within the scope of the claims.

Having thus described my invention, I claim as new and desire to secure by Letters Patent:—

1. A lamp-shade covering, comprising a strip-material formed with a rectilinearly folded longitudinal marginal portion accordion-plaited transversely together with the other longitudinal portion of the strip, joined annularly by the end plaits with the folded portion capable of being expanded circumferentially to force that end of the plaits to retain expanded position, and means contracting the other end of the plaits.

2. The combination with an accordion-plaited lamp shade covering, formed with a circumferential series of perforations throughout all of the plaits at one end of the covering to receive a binding element to contract said end of the covering, of a longitudinally folded and transversely plaited marginal portion at the second end of the covering capable of being expanded circumferentially outwardly from the interior of the covering to retain expanded position when the same is joined annularly by its end-plaits.

3. An accordion-plaited lamp shade covering, consisting of a stiff material strip formed with a longitudinally folded marginal portion plaited transversely with the other portion of the strip and joined annularly by the end plaits with the folded portion interiorly thereof and capable of being expanded circumferentially to keep that end of the plaits expanded and returnable to its normal folded position to contract the covering and means contracting the opposite end of the plaits.

4. A lamp shade covering, consisting of a stiff material strip formed with two longitudinally folded marginal portions accordion-plaited transversely of the folds together with the other portion of the strip and joined annularly by its transverse end plaits with the folded portions interiorly thereof, one of said folded and plaited portions capable of being expanded outwardly circumferentially from the interior of the covering to keep that end of the plaits expanded circumferentially, and a binding element at the other folded portion to contract the second end of the plaits and bind the same against a supporting element.

5. As a new article of manufacture, a stiff material strip rectilinearly folded marginally lengthwise and accordion-plaited transversely to form a lamp-shade capable to retain expanded position when the strip is joined annularly by the end plaits with the folded portion expanded circumferentially.

6. As a new article of manufacture, a stiff material-strip rectilinearly folded on both longitudinal margins thereof, flutes or plaits formed on the strip transversely with said folds to form a lamp-shade capable to retain expanded position, without the employment of a supporting frame, when the strip is joined annularly by the end flutes or plaits with one of the longitudinal folds expanded circumferentially, and means comprising perforations throughout all of the flutes or plaits crossing the other longitudinal fold.

to receive a binding element to contract that end of the flutes or plaits.

7. A lamp shade covering, consisting of a stiff material strip formed with two longitudinally folded marginal portions accordion-plaited transversely of the folds together with the other portion of the strip, and joined annularly by its transverse end plaits with the folded portions interiorly thereof, one of said folded and plaited portions capable of being expanded outwardly circumferentially from the interior of the covering to bring the upper edge of the plaits of the expanded fold in a perpendicular relation with the lower edge of the other portion of the plaits expanding the fold-line circumferentially, a series of perforations throughout all of the plaits crossing the other folded portion circumferentially, an elastic string or cord inserted thru said perforations with its end portions projecting outwardly from an adjacent pair of said perforations, and a knot at the projecting portions of said string or cord to contract the plaits and yield at the insertion of a lamp bearing top element interiorly of the contracted portion.

8. A lamp-shade covering of the class described, comprising a strip material formed with a plurality of rectilinearly scored longitudinal folds to reinforce the same, and flutes or plaits formed on the strip transversely with said folds.

9. A lamp-shade of the class described, comprising a strip material formed with a plurality of rectilinearly scored longitudinal folds, flutes or plaits formed on the strip transversely with said folds, joined annularly by the end flutes or plaits with one of the longitudinal folds capable of being expanded circumferentially to cause expansion at the adjacent end of the flutes or plaits.

10. The method for preparing the strip-material blank for a lamp-shade of the class described, which consists in scoring and folding the strip marginally lengthwise as the same is pulled or drawn from a strip-material supply roll by the action of a plaiting machine which plaits the folded strip transversely, and then cutting the folded and plaited strip into blanks of desired lengths.
